UNITED STATES PATENT OFFICE.

ROLAND MARSLAND, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE BLADING.

Application filed May 31, 1922. Serial No. 564,749.

To all whom it may concern:

Be it known that I, ROLAND MARSLAND, a citizen of the United States, and a resident of Essington, in the county of Delaware and State of Pennsylvania, have invented 5 a new and useful Improvement in Turbine Blading, of which the following is a specification.

My invention relates to turbine blading, 10 more particularly to blading of the wide type adapted to receive steam axially and to discharge it peripherally, and it has for its object to provide apparatus of the character designated which may be more easily 15 manufactured and which, for the same strength, employs less material than heretofore required for blading of this type.

Apparatus embodying features of my invention is illustrated in the accompanying 20 drawings, forming a part of this application, in which: Fig. 1 is a longitudinal sectional view of a turbine showing my improved blading applied thereto; Fig. 2 is an enlarged sectional view taken along the line 25 II-II of Fig. 1; Fig. 3 is an enlarged detail view showing one of the blade sections and Figs. 4 and 5 are detail views of a modified form of blade.

In the application of Alexander T. Kastley, Serial No. 486,517, filed July 21, 1921, 30 continued as Serial No. 521,872, filed December 12, 1921, and assigned to the Westinghouse Electric and Manufacturing Company, there is disclosed and claimed a type 35 of wide exhaust turbine blade which is adapted to receive steam axially and to discharge it peripherally. It is characteristic of the type of blading disclosed in this application that each blade comprises an inner

40 approximately radial or plane portion and an outer curved or spoon-outline portion. In order to avoid bending moments being imposed upon the inner plane portions of the blades, it is necessary to design the 45 outer curved spoon-outline portions so that the sum of the centrifugal moments of portions thereof with respect to a median thickness line of the plane portion shall be equal to zero; and, in order to resist stresses applied at the middle portion of the curved or spoon-outline blade portion, it has been heretofore necessary to thicken that portion particularly at the middle.

50 In accordance with my invention, I provide a blade with an outer curved or spoon-

outline portion, which is made of approximately uniform thickness and which is strengthened by being radially corrugated; and, by extending these corrugations well toward the root of the blade, it may be 60 stiffened against lateral vibration.

Referring now to the drawings for a more detailed description of my invention, I show a turbine comprising a rotor 10, having journal portions 11, fitting in bearings 12, carried by the casing or cylinder 13, the casing or cylinder and the rotor being provided with energy-abstracting elements for abstracting energy from steam supplied from the conduit 14, and after the available energy is abstracted, the steam enters the exhaust chamber 15 communicating with a suitable exhaust outlet, not shown.

I show the conduit 14 communicating with one or more nozzles 17 of a multi-velocity 75 impulse stage comprising moving rows of blades 18, carried by the rotor 10 and a row of re-directing blades 19 interposed therebetween. After being discharged from the last row of moving blades 18, the steam is then fractionally expanded by the stages 80 comprised by the stationary and moving rows of blades 20 and 21 carried by the cylinder or casing 13 and the rotor 10, respectively; and, after being discharged from the last row of moving blades 21, the steam 85 then passes between the guide blades 22 for entry between the wide exhaust blades 23, from which it is discharged peripherally to the exhaust chamber 15. The particular 90 construction of the blading 18, 19, 20 and 21, constitutes no part of my invention and it is referred to for illustrative purposes only.

The wide exhaust blades 23 comprise inner substantially radial or plane portions 24 and outer curved or spoon-outline portions 25, the latter portions being adapted to expand and discharge the steam at small angles peripherally. The blades 23 are 100 preferably made up of a plurality of sections 27 in order to facilitate manufacture.

The outer curved or spoon-outline portions 25 are made of metal of substantially uniform thickness; and, in order to provide 105 adequate strength to resist centrifugal bending moments, the outer blade portions are corrugated in substantially radial directions, as may be seen from Figs. 2 and 3.

Referring to Fig. 3, it will be seen that, 110

in order to avoid bending stresses at the section $a-a$, the centrifugal moments to the left of the center line $c-c$ should be balanced by those to the right of that line. 60
6. This requirement has heretofore been satisfied by thickening the bottom portion of the curved or spoon-outline portion in order to provide sufficient area in stress approximately at the position indicated by the line 65
10 $b-b$ to resist the centrifugal bending moments due to the portion of the blade above the latter line. In accordance with my invention, the portion above the line $a-a$ and constituting the curved or spoon-outline portion 70
15 may be made of substantially uniform thickness, adequate strength being provided in order to resist bending moments by radially corrugating the blade portions in the manner shown in Figs. 2 and 3.
20 20. In order to stiffen the entire blade structure against lateral vibration, the corrugations above described may be extended nearly to the root of the blade as indicated at 30-30 in Figs. 4 and 5. Obviously, these 25 corrugations in the main body of the blade would not be of a depth permissible in corrugations confined to the spoon tip, inasmuch as they lie more or less transverse to the steam path and would render the same 30 too tortuous if of excessive depth.

From the foregoing, the operation of apparatus made in accordance with my invention will be well understood: Steam is expanded in the usual way in the blading, and 35 my novel construction of the outer portions of the wide exhaust blades, permits of the latter being made of substantially uniform thickness, and, at the same time, with the preservation of sufficient strength to resist 40 centrifugal bending moments.

While I have shown my invention in but one form, it will be obvious to those skilled in the art that it is not so limited, but is susceptible of various other changes and 45 modifications, without departing from the spirit thereof, and I desire, therefore, that only such limitations shall be placed thereupon as are imposed by the prior art or as are specifically set forth in the appended 50 claims.

What I claim is:

1. In a turbine, a row of blades having portions normally subject to centrifugal bending moments, said portions being corrugated radially in order to resist said moments. 55
2. In a turbine, a row of blades having

outer curved discharging portions provided with radially extending corrugations in order to strengthen the curved portions. 60

3. In a turbine, a row of blades having curved portions subject to centrifugal bending moments and which are corrugated radially in such a direction as to strengthen the blades and not to interfere with the steam flow. 65

4. In a turbine, a row of blades adapted to receive steam axially and to discharge it peripherally comprising inner plane portions and outer curved or spoon-outline portions for expanding and discharging steam peripherally at small angles, each of the blades being composed of a plurality of sections and having the outer curved or spoon-outline portions of substantially uniform thickness and the latter portions being corrugated in order to strengthen them. 70

5. In a turbine, a row of blades adapted to receive steam at one side and to discharge it at the tips, comprising inner substantially plane portions and outer curved portions for discharging the steam at small angles, said outer portions being corrugated substantially normally to the tips in order to strengthen the outer curved blade portions. 75 80

6. In a turbine, a rotor blade having a substantially flat body portion parallel to a radial plane, and radial corrugations in said body portion adapted to stiffen the same against lateral vibration. 85

7. In a turbine, a rotor blade having a substantially flat body portion parallel to a radial plane and terminating in a spoon-shaped tip having a small leaving angle, and substantially radial corrugations in said body portion and in said tip adapted to stiffen the entire blade structure against lateral vibration and to stiffen said tip against the action of centrifugal force. 90

8. In a turbine, a row of blades adapted to receive fluid axially and to discharge it peripherally comprising inner plane portions and outer curved or spoon-outline portions for expanding and discharging steam peripherally at small angles, each of the blades being composed of a plurality of sections and each of the sections being corrugated substantially throughout its length in order to stiffen the same against forces acting transverse thereto. 100 105

In testimony whereof, I have hereunto subscribed my name this 26th day of May, 1922.

ROLAND MARSLAND.
